UNITED STATES PATENT OFFICE.

ALBERT L. WHITE, OF CHICAGO, ILLINOIS.

PRACTICE-KEYBOARD APPARATUS.

1,169,586.

Specification of Letters Patent.

Patented Jan. 25, 1916.

Application filed December 7, 1910. Serial No. 596,020.

To all whom it may concern:

Be it known that I, ALBERT L. WHITE, a citizen of the United States, residing at Chicago, in the county of Cook and State of Illinois, have invented a certain new and useful Improvement in Practice-Keyboard Apparatus, of which the following is a specification.

This invention relates to improvements in practice key-board apparatus, and has for its object to provide a new and improved device of this description.

The invention is illustrated in the accompanying drawings, wherein—

Figure 1 is a front view of one form of device embodying the invention; Fig. 2 is a sectional view taken on line 2—2 of Fig. 1; Fig. 3 is an enlarged sectional view with the parts collapsed and the casing closed ready for transportation; Fig. 4 is a sectional view taken on line 4—4 of Fig. 3; Fig. 5 is a sectional view taken on line 5—5 of Fig. 2; Fig. 6 is a view showing the operating mechanism for the up-click; Fig. 7 is a sectional view taken on line 7—7 of Fig. 6; Fig. 8 is a sectional view taken on line 8—8 of Fig. 2; Fig. 9 is a view showing the actuating springs for the bellows.

Like numerals refer to like parts throughout the several figures.

This invention relates particularly to a practice device for pianists. The device is arranged so that it can be easily transported from place to place, so that it can be used by persons while traveling in order that they may keep in practice.

Referring, now, to the drawings, the device is inclosed in a collapsible casing 1, the lower part 2 of which is hinged at 3 and 40 is removably attached to the upper part by the hooks 4. A cover 5 is hinged at 6 to the casing so that it may be moved out of the way to expose the keys. Within the casing are a series of keys 7 and 8 similar to piano 45 keys. The keys 7 may be arranged in position in any desired manner. As herein shown the keys 7 are pivoted upon the pins 9, and the keys 8 are pivoted upon the pins 10, said pins being carried by the piece or 50 balance rail 11 mounted upon the support 12. The front ends of the keys are provided with guides 13. Some means is provided for returning the keys to their normal position after being pressed down by the fingers of 55 the operator. As herein shown each key is provided with a retracting spring 14, said

springs being connected with a longitudinal supporting piece 15. A limiting device 16 is provided for limiting this return movement. Near the end of each key there is 60 preferably provided a coil spring 17 which is adapted to engage a rail 18 which produces an increased resistance in these springs as the rear ends of the keys are moved up in response to the touch of the 65 operator. The springs 17 are preferably arranged so that their ends do not touch the compressing device when the keys are in their normal position. It will be noted that by means of this construction the downward 70 movement of the front ends of the keys is resisted by a gradually increasing resistance due to these springs, thus securing an action approximating that of a piano so as to give the operator the same benefit secured by 75 practising on the piano.

Means is provided for varying the action of the instrument, that is, for increasing or decreasing the force required to manipulate the keys, so that between certain ranges any 80 desired action may be secured. As herein shown the keys are provided at their rear ends with the springs 19, the upper ends of which are free. As the rear ends of the keys move up these springs are adapted to engage 85 a resisting device 20. This resisting device as shown in the drawings consists of a movable piece extending across the keys and mounted in suitable guides 21 in the frame. This resisting device preferably has a curved 90 face at the points where the springs 19 make contact therewith, this curved face being preferably covered with a soft covering 22. It will be seen that by moving the resisting device 20 toward the springs 19 the resistance to the upward movement of the rear 95 ends of the keys will be increased, and that by moving said resisting device away from said springs this resistance will be decreased. The movement of the resisting device as 100 herein shown is secured by means of an actuating part 23. This actuating part consists of a cam device pivoted at 24 and having its cam face engaging the resisting device 20 so that when moved about its face 105 this resisting device may be moved back and forward. Some anti-friction construction is preferably provided, as, for example, by providing the rollers 25 at the contact face 110 of the parts. Suitable retracting springs 26 retract the resisting device. These springs 26 also have another function. It will be

noted that the cam 23 engages the resisting device near its middle, and hence the resisting device is liable to be moved forward unevenly, thus acting on some of the springs 5 and not the others. The springs 26 insure an even forward movement of the resisting device. A controlling handle 27 is connected with the actuating part 23 and projects through a slot 28 in the wall 29 so that the 10 end thereof is in position to be easily manipulated by the operator. This handle is preferably movably connected with the actuating part so that it may be lengthened when it is desired to move the actuating part 15 in order to secure a proper lever arm, and may then be pushed back out of the way. This result is secured by providing the part 27 with the slot 30, through which pass the pins 31 connected with the actuating part. 20 There is preferably associated with the slot 28 a scale, as shown, the figures thereon indicating the degree of resistance offered by the resisting device when the controlling handle is moved opposite to said figures, thus permitting the operator to easily and quickly 25 regulate this resistance as desired.

Means are provided for producing a clicking sound both when the keys are pressed down by the operator and when they return to their normal position after being released. 30 These devices I have termed the up and down clicks. The down click consists of a movable piece 32. This movable piece is hinged, as shown in Fig. 3, so that it may 35 be moved to an operative or an inoperative position. As herein shown the movable piece is controlled by means of a handle 33, pivoted between its ends and located at one end of the key-board, said handle being 40 connected to the movable piece 32 by means of the link 34. When the handle 33 is moved so as to set the movable piece 32 upon its edge, as shown in Fig. 2, the keys when actuated will strike the movable piece 32 making 45 a clicking noise. This clicking noise indicates the proper operation of the keys by the operator. When the part 32 is in the position shown in Fig. 3 it is in its inoperative position and there will be no clicking 50 noise when the keys are pressed down. The up-click comprises a bar 35 located near the rear end of the keys and arranged so that it may be raised into a position to be struck by the keys when they are released by the 55 operator, thus producing a clicking sound. This bar may be actuated in any desired manner. As herein shown it is supported upon a sliding piece 36 which slides upon wedges 37 when moved in one direction, so 60 as to lift the bar 35 to its operative position. When the piece 36 is slid in the other direction it drops down over these wedges and lowers the bar. An adjustable limiting device 38 is arranged for limiting the upward 65 movement of the bar 35. As herein shown

the sliding piece 36 is actuated by means of a handle 39 pivoted between its ends, similar to the handle 33, and having its lower end connected with a rod 40 (see Fig. 5). This rod 40 is connected to the curved arm 41 pivoted at 42 (see Fig. 6), said arm being connected with the sliding piece 36. The bar 35 and sliding piece 36 are located between guides 43. The up click, in addition to other uses, may be used to indicate to the operator 70 the simultaneous movement of different keys in opposite directions. If, for example, one key should be released and another pressed down simultaneously, this simultaneous movement will be indicated when the up and down clicks come together, so that there will be only one click heard. When the operator desires to use the machine where the clicks would be objectionable, they may both be rendered inoperative. 75

This device may be arranged so that the proper musical tones may be produced when the keys are depressed. For this purpose I have shown an organ construction. Each key is provided with its proper reeds 44, associated with the openings 45 controlled by the valve 46, normally held in place by the spring 47. Associated with each key is a pin 48 which presses down its associated valve so as to open it. The reeds are made to vibrate by a current of air drawn through the openings 45 by suitable bellows. As herein shown there are two reeds for each key. One set of reeds is provided with a suitable mute. The mute 49 at the front 95 of the apparatus is hinged at the top, as shown in Figs. 2 and 3, and is held in its operative position by one or more springs 50. This mute is opened by means of a lever 51, adapted to be actuated by the knee 100 of the operator. This lever has a part 52 rotatably mounted in the bracket 53, the end being provided with a crank 54 to which is connected a cord 55 attached to one end of the bell crank lever 56. The other end of this bell crank lever is connected to the mute 49 by the piece 57. By a movement of the knee, therefore, this mute may be controlled so as to control the volume of the sound. There is a swell 58 at the back 115 of the device (see Figs. 2 and 3). The swell 58 is controlled by the lever 59 through the agency of the knee of the operator. This lever is provided with a crank 60 to which is connected a cord 61 (see Figs. 1 and 4). 120 The cord 61 is connected to the crank 62 on the shaft 63. This shaft is also provided with a crank 64 which engages a projection 65 connected with the swell 58. It will thus be seen that when the lever 59 is moved 125 by the knee, the shaft 63 will be rotated so as to lift the swell 58. Connected with the swell 58 by one or more rods 66 is a hinged door 67 at the back of the casing. By means of this connection this door will 130

be opened when the swell is lifted, so as to permit the free escape of the sound.

The air is drawn down through the openings 45 by means of any suitable mechanism.

5 As herein shown organ bellows are used. A pedal 68 is connected by a connecting piece 69 with the lower side 70 of the bellows, which has openings 71 controlled by the flexible valve 72. The part 70 has a hinged 10 connection with the part 73, which is also provided with holes 74 controlled by a flexible valve 75. A spring 76 tends to normally move the parts 70 and 73 toward each other. The parts 70 and 73 are connected by a 15 suitable web 77, while the part 73 is connected with the part 78 by a similar web 79. A spring 80 tends to separate the parts 73 and 78. The part 73 is hinged and preferably extends entirely across the device, 20 but there are two parts 70, one connected with the pedal 68, and the other connected with the pedal 81, so that they can be alternately moved. In the operation of the device when the pedals are moved down, the 25 parts 70 are separated from the part 73 and air is drawn through the holes 74, this movement causing the valve 72 to close, and the valve 75 to open. When the pedal is released the spring 76 moves it back, the 30 valve 75 being now closed and the air between the parts 73 and 70 escaping through the openings 71. As the air is drawn from between the parts 73 and 78 the part 73 tends to collapse, a partial vacuum being produced. 35 If, now, a key is pressed, so as to open one of the valves 46, air will be drawn through the openings 45 so as to vibrate the reeds and produce the musical tone corresponding to such key.

40 The entire device may be folded up, as shown in Fig. 3, when it is desired to transport it from place to place. The bottom 2 of the casing is hinged at 3 and when the device is in use stands in a vertical position, as 45 shown in Fig. 2. The device is provided with the folding legs 84 and 85. Each of these folding legs consists of a rectangular frame hinged to the casing by the hinges 86. When the device is ready for operation, 50 as shown in Figs. 1 and 2, the legs 84 and 85 are connected by a cross piece 87. This cross piece is removably connected with the legs in any desired manner. As herein shown each end of the cross piece is provided 55 with a metal piece 88. Each leg is provided with a loop 89 having a branch 90 which fits into the loop 91 of the piece 88 (see Fig. 8). Associated with each leg is a brace consisting of two parts 92, pivoted to- 60 gether near their middle (see Fig. 2), so that, when in alignment, they can be bent in one direction to close them up, but are locked against being bent in the opposite direction by means of the locking lug 93. These 65 braces are fastened to the cross piece 87 (see

Fig. 8). The bottom 2 of the casing is provided with hooks 94 which are hooked into eyelets connected with the legs. The pedals 68 and 81 are pivotally connected with the cross piece 87. When it is desired to fold 70 the device, the bellows are moved so that the engaging part 95 slips over the hook 96 so as to hold the bellows in a collapsed position. The cross piece 87 is then disconnected from the legs and the braces 92 bent 75 by moving the pivotal points upwardly. This movement turns the pedals upside down, and the pedals are then folded up against the bellows (see Fig. 3). The two 80 pedals when folded are in the same plane and are located side by side. The legs 84 and 85 are then disconnected from the bottom 2 and are moved about their hinges so as to be folded up under the pedals. One of the legs—the leg 85—is hinged higher up 85 than the other, a distance equal to the thickness of the leg, so that the two legs will fit snugly one under the other, as shown in Fig. 3. The bottom 2 is then folded up and is connected to the upper part by the hooks 4. 90 The cover 5 is also folded down and locked in position by the hooks, and the device is then ready for transportation. It can be carried around like a valise by means of the handles 97. When the device is to be operated, the parts are unfolded and placed in position, as shown in Figs. 1 and 2. The bottom 2 of the casing is provided at one end with a projecting part or lip 98, cut away at each end so as to leave a free space 100 at each end. In other words this lip is shorter than the bottom piece 2 and passes between the legs 84 and 85 when the casing is open and the parts are in position for use, as shown in Figs. 1 and 2. The legs therefore engage the piece 2 and also the ends of the lip 98. When the hooks 94 are hooked it will be seen that the legs are firmly held in position and movement or rocking thereof is prevented. The springs 76 are provided 105 at one end with the coils 99 and are fastened in position at the ends having the coils, in any desired manner, to the part 73. The other ends of the springs are provided with laterally projecting engaging parts 101, 110 which engage the lower sides 70 of the bellows, and normally tend to move them toward the part 73.

I claim:

1. A practice keyboard device comprising 120 a series of keys, a spring connected with each of said keys and having a projecting part, a sliding bar engaging the projecting parts of said springs, guides for said bar, a cam in proximity to said bar and when actuated 125 moving it toward the projecting parts of said springs, and means separate from said cam, for insuring an equal forward movement of said bar throughout its length.

2. A practice keyboard device comprising 130

1. A series of keys, a spring connected with each of said keys and having a projecting part, a sliding bar engaging the projecting parts of said springs, guides for said bar, a cam in proximity to said bar and when actuated moving it toward the projecting parts of said springs, and means separate from said cam, for insuring an equal forward movement of said bar throughout its length, said bar and cam being in the same horizontal plane, and a series of rollers through which the pressure due to the movement of the cam is transmitted to the bar.
2. A practice key-board device comprising a series of keys, a resisting part adapted when in predetermined positions to resist the movement of said keys in varying degrees, a cam piece in proximity to said resisting part and when actuated, moving it to various positions, a handle connected with said cam piece and projecting within reach of the operator, and a scale along which said handle is adapted to be moved, said handle adjustably connected with the cam piece whereby the distance it projects therefrom may be varied.
3. A practice key-board device comprising a series of keys, a resisting part adapted

when in predetermined positions to resist the movement of said keys in varying degrees, a cam piece in proximity to said resisting part and when actuated, moving it to various positions, and a retracting device associated with said resisting part and adapted to move it toward the cam piece as the engaging face of the cam piece is moved away from the resisting part.

4. A practice key-board device comprising a series of keys, a resisting part adapted when in predetermined positions to resist the movement of said keys in varying degrees, a cam piece in proximity to said resisting part and when actuated, moving the resisting part to various positions, two retracting springs connected with said resisting part, one on each side of said cam piece, said springs adapted to keep the resisting part in contact with the engaging face of the cam piece.

Signed at Chicago, Illinois, this 2nd day of December, A. D. 1910.

ALBERT L. WHITE.
